APPARATUS FOR IMMERSING EDGE PORTIONS OF BLACK PLATE IN SUCCESSIVE TREATING BATHS

Walter M. Tomkins and Albert C. Larkin, Pointe St. Charles, Montreal, Quebec, and John C. Anthony and Oakland K. Ross, St. Laurent, Quebec, Canada, and Ralph M. Mero, Chicago, Ill., assignors to Continental Can Company, Inc., New York, N. Y., a corporation of New York

Application August 9, 1943, Serial No. 497,982
In Canada August 3, 1943

7 Claims. (Cl. 134—67)

1

This invention relates to apparatus for preparing black plate blanks, especially "bonderized" plate blanks, for the formation of can bodies having solder-bonded side seams. Difficulty has been encountered in the forming of solder-bonded side seams of can bodies made from black plate because the plate stock, when exposed to air, oxidizes and forms a scale which interferes with the soldering of the side seam. According to the present invention, the edge portions of plate blanks to be formed into side seams are cleaned, preferably cathodically, and are then coated or plated with a material, e. g. tin, which is resistant to oxidation and which has an affinity for a solder bond.

An object of the invention is to provide a machine of the character stated in which edge portions at opposite ends of a blank are treated or prepared individually.

Another object of the invention is to provide a machine for treating blank side edge portions in which the blanks are moved edgewise through a fluid.

Another object of the invention is to provide a machine for the kind referred to in which the handling of the blanks and sequence of operations is carried out in a new and facile manner conducive to rapid operation.

Another object of the invention is to provide apparatus for simultaneously treating or preparing the edge portions of a group of individual blanks simultaneously.

Another object of the invention is to provide new and improved means for releasably clamping blanks and supporting them on a conveyor.

Another object is to provide novel apparatus for transferring blanks or groups of blanks from one conveyor to another.

Another object of the invention is to provide mechanism for reversing the position of blanks carried by treating conveyor mechanism so that opposite edge portions of the blanks may be presented in turn for treatment.

Another object of the invention is to provide means for moving blanks edgewise through a treating bath.

A further object of the invention is to provide apparatus of the character referred to in which adjustments can be effected for adapting the

2

apparatus for the handling and treatment of blanks of different sizes.

Other objects of the invention will become apparent from a reading of the following description, the appended claims, and the accompanying drawing.

In the drawings:

Figure 1 is a flow diagram indicating schematically the sequence in which the steps may be performed in practicing the method;

Figure 2 is a vertical sectional view of enameling apparatus;

Figure 3 is a perspective view of a prepared blank;

Figure 4^a is a somewhat diagrammatic front elevation of apparatus embodying the invention in one form showing portions of the apparatus on one side of a line IV—IV;

Figure 4^b is a view similar to Figure 4^a but showing apparatus on the other side of the line IV—IV, it being intended that Figures 4^b and 4^a be read together as if joined along the line IV—IV;

Figure 5 is an elevation of one form of gripping means for releasably holding a group of blanks on a conveyor, guides or tracks for the conveyor being shown in section;

Figure 6 is a plan view of the gripping means shown in Figure 5 as viewed when looking in the direction of the arrow 6 in Figure 5;

Figure 7 is an elevation of a second form of gripping means assembly;

Figure 8 is a section on the line 8—8 of Figure 7.

Figure 9 is a detail section on the line 9—9 of Figure 7, drawn on an enlarged scale;

Figure 10 is a detail section on the line 10—10 of Figure 7, drawn on an enlarged scale;

Figure 11 is a detail section on the line 11—11 of Figure 7, drawn on an enlarged scale;

Figure 12 is a fragmentary plan view, on an enlarged scale, of a pusher bar equipped with guide clips for receiving the trailing edges of blanks carried by the gripping means shown in Figures 7 to 11 inclusive;

Figure 13 is a fragmentary top plan view, on an enlarged scale, showing the mounting of a pusher bar hanger as viewed when looking in the direction of the arrow 13 in Figure 7.

Figure 14 is an elevation of a third form of gripping means assembly;

3

Figure 15 is a plan view of the assembly shown in Figure 14 as seen when looking in the direction of the arrow 15 in Figure 14.

Figure 16 is a detail section on the line 16-16 of Figure 14, drawn on an enlarged scale;

Figure 17 is a diagrammatic perspective view showing a plurality of grouped blanks being moved through a treating bath; and

Figure 18 is a fragmentary elevation of cam and lever mechanism for operating a blank gripper actuating cam, a drive shaft being shown in section.

A preferred sequence in which a series of operations may be performed in preparing individual blanks for the formation of can body solder bonded side seams is indicated schematically in Figure 1. A ribbon or web 1 of black plate stock which has been "bonderized," i. e., coated with zinc phosphate, is drawn by suitable rolls 2 through an enameling apparatus generally designated 3 for coating both sides of the web 1 with enamel but leaving marginal portions at each side of the blank bare or unenameled. The enameling apparatus 3 includes a first tank 4 containing enamel indicated at 5, a transfer roll 6 and an applicator roll 7 for applying enamel to one flat surface of the web 1. The apparatus 3 further includes a second tank 8 containing enamel 9 adapted to be picked up by a transfer roll 10 and supplied to an applicator roll 11 arranged to apply enamel to the opposite flat surface of the web 1. As shown in Figure 2, the web edge portions *x* and *y* extend laterally beyond the applicator rolls 7 and 11 so as not to be coated with enamel.

After leaving the drawer roll 2 the web 1 passes through an oven or drying apparatus indicated at 12 and which may be of any conventional or suitable form, and then passes to a shear or other suitable severing means indicated at 13 for cutting off individual plate blanks 14, later to be formed into can bodies. It is apparent that although the enameling of a continuous web followed by the cutting off of individual plate blanks 14 provides for rapid operation, the enameling of individual blanks after they have been cut to size would provide equivalent results since in either case the individual blanks would have corresponding enameled surfaces and unenameled edge portions. The specific apparatus employed and procedure followed in enameling the blank material is not of particular importance.

In accordance with the invention, the blanks are moved to a treating bath and the lower edge portion only of each blank is projected into treating fluid, the blank then being withdrawn from the fluid, reversed, and the other unenameled edge portion is projected into the fluid for similar treatment. Preparatory to treating each blank in this manner, it is placed vertically as indicated at 14^a in Figure 1. The blank is then moved over a treating bath container 15 and is projected downwardly to the position indicated at 14^b so that the unenameled lower edge portion *y* is immersed in a cleaning fluid 16, the line of demarcation between the unenameled edge portion *y* and the enameled portion of the blank being substantially at the level of the fluid 16. The blank may then be moved horizontally through the fluid 16 while the cleaning operation is being performed. The blank should be moved edgewise so as to cut through the fluid without creating waves, ripples or other disturbances. In this way the level of the fluid 16 will not rise and fall above the line of demarcation between the

4

unenameled edge portion *y* and the enameled part of the blank. Consequently, the cleaning fluid will not attack the enamel.

In accordance with a further feature of the invention, a plurality of blanks are moved in a group through the treating fluid 16, the grouped arrangement of the blanks being such that all of the individual blanks move edgewise through the fluid. Figure 1, which is schematic, shows only one blank 14, but it will be understood that in practice it is advantageous to move a plurality of grouped blanks through the treating fluid. As will be explained in the description of a preferred form of apparatus, the groups advantageously may comprise six blanks as shown in Figure 17. The moving of the blanks edgewise is particularly advantageous when the blanks are treated in groups. It will be apparent that if in the treatment of a group of blanks the blanks were to move flatwise, the waves or ripples created by one or more of the blanks would raise into contact with the enamel portion of other blanks, thereby harming the enamel coatings.

The cleaning of the unenameled edge portions preferably is accomplished cathodically. For this purpose an anode 17 is immersed in the fluid 16 and the blank 14 is arranged to make contact with a bus bar 18. The anode 17 and bus bar 18 are adapted to be connected to a source of current by means of conductors 19. The electrolyte or fluid 16 preferably comprises a ten percent to fifteen percent sulphuric acid bath at room temperature, e. g., 70° to 80° F. The liberation of hydrogen on the unenameled edge portions *y* mechanically aids in loosening the phosphate film which is dissolved in the acid bath solution.

The blanks may travel approximately three feet through the cleaning liquid during an immersion period of about ten seconds, that is, at a rate of three-tenths foot per second. The path of travel through the fluid need not be exactly three feet because the times during which the blanks are being lowered into the liquid and are being raised from the liquid are to be added to the time during which they travel horizontally in order to determine the total treating period. A net treating period of ten seconds is preferred, and, therefore, the horizontal travel may be somewhat less than three feet. Application of a E. M. F. of three volts to the anode 17 and bar 18 will produce a current of about thirty amperes.

After the cleaning of the unenameled edge portion *y* each blank is withdrawn from the fluid 16. It is not necessary to remove cleaning fluid adhering to the blanks after withdrawal from the cleaning fluid, but some saving of cleaning fluid may be effected by mechanically removing the adhering fluid by the use of squeegee rolls or other suitable means.

When the blank has been removed from the cleaning fluid 16 its edge portion *y* will be clean and unencumbered, the "bonderized" coating having been removed. The blank is then moved over a plating tank or container 20 and lowered so as to project the edge portion *y* into plating fluid 21, the blank then being in the position indicated at 14^c in Figure 1.

The edge portion *y* then is plated with an oxidation resistant material having an affinity for a solder bond. Several ways of forming such a plating are known. For example, in United States Patent 2,304,931 to Kronquest, blank edge portions are prepared for forming solder bonded side seams by being dipped in copper sulphate

5

solution. According to the present invention it is preferred to electroplate the blank edge portions with tin. The electrolyte 21 in the tank 20 may comprise the following constituents substantially in the proportions indicated:

	Ounces
Tin (stannous)	4-5.6
Free sulphuric acid	6.4-11.2
Cresol sulphonic acid	11.2-19.3
Gelatine	1/3
Beta-naphthol	1/6
Water (distilled) to make 1 gallon	

An anode 22 preferably of pure tin is immersed in the electrolyte 21. A bus bar 23 is arranged to be in electrical contact with the blank during the electroplating operation. The anode 22 and bus bar 23 are adapted to be connected to a source of current by conductors 24.

During the electroplating operation the blank or blanks are moved edgewise through the fluid 21 the same as was done during the cleaning operation.

The cresol sulphonic acid acts as a solution stabilizer and prevents atmospheric oxidation. The gelatine and beta-naphthol are additional agent for providing tin deposits which are smooth and bright and have good covering qualities.

The temperature of the plating bath, as well as the immersion period and travel of the bodies in the bath are the same as for the cleaning bath.

The plating time is approximately ten seconds with a current of 1.5 volts and 16 amperes, and the anode current density is about 4.5 amperes per square foot.

The average thickness of the tin coating determined from a number of samples is found to be .000027 inch.

After the cleaning and treating of the blank lower edge portion *y*, the blank is reversed or inverted so as to be in the position indicated at 14^a in Figure 1, with the edge portion *x* at the bottom. This edge portion is then treated in a cleaning tank 25 containing fluid 26. A lead anode 27 and bus bar 28 are adapted to be connected by conductors 29 to a source of current. After the edge portion *x* is cleaned, the blank is moved to the position indicated at 14^b. The edge portion *x* is within a tank 30 and immersed in plating fluid 31. A tin electrode 32 and bus bar 33 are adapted to be connected to a source of current by conductors 34. After the edge portion *x* has been plated the blank is withdrawn, a blank 14 with both edge portions *x* and *y* cleaned, plated, and ready for the formation of a container body side seam being indicated at 14^c.

Figures 4^a to 16 inclusive disclose apparatus embodying the invention and suited for practicing the hereinabove described method rapidly. Considered in its general nature the disclosed apparatus includes mechanism generally designated A for feeding individual blanks to a grouping means B which serves to assemble and position the blanks in spaced relation to each other in parallel planes. The grouping means B comprises a conveyor which moves the group blanks crosswise with respect to the direction of movement of a transfer conveyor generally designated C.

The conveyor C is equipped with means later to be described for simultaneously picking up the blanks 14 of a group of six blanks, and moving them to the position indicated at 35 in Figure 4^a for transfer to a lower treating conveyor D. The conveyor D receives the blanks from the transfer

6

conveyor C and carries them in groups suspended from its lower stretch to move downwardly at 36 for projecting the blank lower edge portions into the cleaning bath tank 15, then raising the blanks 5 and thereafter again lowering the blanks as at 37 for projecting their bottom edge portions into the plating tank 20. The blanks then move on to the transfer position indicated at 38 where they are released from the lower treating conveyor 10 and picked up on an upper treating conveyor E positioned above the conveyor D. When this transfer has been effected, the blank edge portions which were treated in the tanks 15 and 20 will be held by the upper treating conveyor 15 E so as to leave the opposite edge portions extending downwardly, the blanks having thus been inverted or reversed. The blanks move along with the lower stretch of the conveyor E to follow the path indicated in Figures 4^a and 4^b until 20 moved downwardly as at 39 so as to have their bottom edge portions projected into cleaning fluid in the tank 25. After passing beyond the tank 25 the blanks again are lowered as at 40 for having their lower edge portions projected into the plating 25 bath in the tank 30. After being moved through and raised clear of the tank 30, the blanks move on to a point of discharge indicated at 41 in Figure 4^a.

The mechanism A for effecting initial feeding 30 of the blanks is adapted to take or receive individual blanks successively from the bottom of a stack held, for example, by a magazine (not shown), the bonderized blanks 14 held in the magazine having previously been enameled with 35 the exception of opposite edge portions *x* and *y*.

In operation a group of six blanks received by 40 the conveyor B will be moved to the top stretch and will be positioned as indicated at 14 in Figure 4^a. The blanks of the group will be disposed vertically and spaced relative to each other, lying in mutually parallel planes.

When a group of six blanks has reached the 45 position 14, the conveyor B is stopped and the group of blanks is moved transversely of the direction of conveyor movement, that is to the right as viewed in Figure 4^a for being picked up and carried away by the transfer conveyor C.

The transfer conveyor mechanism C includes 50 three parallel shafts 122, 123 and 124 mounted to rotate on brackets secured to the frame. The shaft 122 carries a pair of spaced sprockets 127, the shaft 123 carries a pair of similarly spaced sprockets 128, and the shaft 124 has secured thereto in similarly spaced relation a pair of drive sprockets 129. Conveyor chains 130 are trained respectively one around each complement of sprockets 127, 128 and 129. A plurality of blank gripper or releasable holding assemblies 131 is carried by the spaced chains 130, the gripper assemblies 131 being spaced from each other along the chains 130. When a gripper assembly 131 is opposite the conveyor C the blanks 14 of a group are presented to the conveyor C. Thereafter 65 the gripping assembly is operated to grip or hold the blanks and move them around for delivery to the bottom treating conveyor D. The conveyor C is stopped when each gripping assembly reaches the proper position so that the thus positioned gripping assembly will be at rest when 70 it receives the group of blanks 14 presented by the conveyor B.

The gripper mechanism 131 previously referred to only generally is shown on an enlarged scale 75 in Figures 5 and 6. It includes a cross frame

member 153 equipped at its ends with angle brackets 154 for connection respectively to the chains 130 of the conveyor C. A plurality of fingers 155 spaced from each other correspondingly to the spacing of the blanks of a group is secured to the frame 153 as at 156. An actuating rod or bar 157 mounted to slide through the fingers 155 carries a plurality of similarly spaced fingers 158 movable with the rod 157 relatively to the fixed fingers 155. Rubber pads 159 mounted on the movable fingers 158 respectively are adapted to engage blanks positioned between each pair of fingers 155-158 to clamp the engaged blanks against the associated fixed fingers 155.

A spring 160 is interposed between the movable finger 158 shown at the left in Figures 5 and 6 and a collar 161 on an adjusting screw 162 carried by a bracket 163 secured to the bar 153 by a screw and nut 164-165. The spring 160 constantly urges the bar 157 toward the right so as to move the gripper fingers 158 into gripping position. For opening the grippers to condition the grippers to receive blanks, a roller 166 is journaled on the frame 153 as at 167 and a roller 168 is journaled on the bar 157 as at 169. Normally the rollers 166 and 168 are in the positions shown in Figures 5 and 6. A wedge cam 170 is adapted to move relatively between the rollers 166 and 168. The roller 166 cannot move longitudinally of the rod 157 and therefore entry of the cam 170 between the rollers will move the roller 168 and the rod 157 against the urge of the spring 160 so as to open the grippers.

The gripping devices 131 mounted on the conveyor C are adapted to be operated in time with the operation of the feeding device B, the arrangement being such that when the gripping mechanism is in a receptive position, the grippers will all be open and thus will be conditioned to receive blanks 14 pushed toward the conveyor C. Insertion of the blanks into the open grippers is facilitated by rounded edges 171 on the fixed gripper parts 155. After the blanks have been inserted and while the conveyors B and C are still at rest, the cam 170 is withdrawn from between the rollers 166 and 168 so as to permit the spring 160 to move the rod 157 and close the grippers. Then the conveyor C is driven through the mechanism 132 previously described and after the blanks carried by the grippers are raised above the arms on the conveyor B, the latter is driven again through the intermittent drive mechanism.

The cam 170 must be moved relatively to the rollers 166 and 168 carried on the conveyor C while the conveyor is at rest. Any suitable means may be provided for mounting and moving the cam 170; for example, the cam may be mounted on a rod 172 extending vertically between the conveyors B and C, through a guide 173 carried by a frame shelf 174. The lower end of the rod 172 is pivoted as at 175 to a link 176 in turn pivoted at 177 to one arm of a lever 178 pivoted at 179 on a bracket 180 carried by the frame base 181. The other end of the lever 178 is equipped with a cam follower roller 182 cooperable with a cam 183 fast on the shaft 91. A spring 184 urges the lever 178 to move the rod 172 and cam 170 downwardly and also maintains the roller 182 in engagement with the cam 183.

In operation, the rod 172 will be in its upper position when a gripper device assembly 131 moves upwardly toward the receiving position. As the assembly 131 moves upwardly the rollers 166 and 168 will engage the tapered end of the

cam 170 which then will be held stationary in its upper position by the cam 183 and lever 178. Continued movement of the rollers 166 and 168 while the cam 170 is stationary will cause the roller 168 to move longitudinally of the assembly 131, thereby opening the grippers and conditioning the gripper assembly to receive a group of blanks being fed to it.

The group of blanks is fed into the open grippers on the assembly 131 while the cam 170 is still held in its upper position. When the blanks are in the grippers the cam 183 will move on around to permit the spring 184 to rock the lever 178 and move the rod 172 downwardly. This will withdraw the cam 170 from between the rollers 166 and 168 on the assembly 131, and the grippers will be closed by the spring 160 thereby clamping the group of blanks to the transfer conveyor C.

The treating conveyors D and E are mounted on a frame 185 and are driven continuously in synchronism with each other and at a speed corresponding to the uniform velocity driving speed of the transfer conveyor C. The conveyor D is trained around sprockets 186 shown at the left in Figure 4^a and around sprockets 187 and a drive sprocket 188 shown at the right in Figure 4^b.

The conveyor D is driven by gearing interposed between the shaft 97 and the sprocket 188. A bevel gear 190 on the shaft 97 meshes with a gear 190 fast on a shaft 191. A sprocket 192 on the shaft 191 is connected by a chain 193 with a sprocket 194 fast on one end of a shaft 195 (see Figure 4^a). The other end of the shaft 195 is equipped with a bevel gear 196 meshing with a bevel gear 197 fixed to rotate with the drive sprocket 188.

The bevel gear 196 has a spline connection with the shaft 195 so as to permit adjustment of the gears 196 and 197 together with the sprocket 188 for varying the tension of the conveyor D.

The conveyor E is trained around a drive sprocket 198 shown at the left in Figure 4^a and around sprockets 199-199 and 200 shown at the right in Figure 4^b, and is driven by gearing interposed between the shaft 195 and the drive sprocket 198. As shown in Figure 4^a a sprocket 201 fast on the shaft 195 is connected by a chain 202 with a sprocket 203 secured to a shaft 204. The shaft 204 is equipped with a bevel gear 205 meshing with a bevel gear 206 which is connected to the drive sprocket 198.

Both conveyors D and E are equipped with grippers similar to the grippers 131 previously described with reference to the transfer conveyor C. However, the grippers carried by the conveyors D and E should be insulated from the conveyor chains on which they are mounted and for this purpose the gripper frame elements 153 may comprise insulating blocks indicated at 213 in Figures 5 and 6.

The operation of the transfer conveyor C and bottom treating conveyor D is so timed that when a group of blanks reaches the position indicated at 215 in Figure 4^a the blanks will be gripped by the gripper on the conveyor D and then will be released by the gripper on the conveyor C, the transfer from the conveyor C to the conveyor D taking place while the conveyors are traveling at the same speed. Inasmuch as the grippers are operated during movement of the conveyors, the cams for entering relatively between the rollers 166 and 168 are mounted respectively in fixed positions on the frames carrying the conveyors C and D. The relative positioning of the cams

for effecting the properly timed releasing and grouping of the blanks is indicated in Figure 4^a wherein a cam shown at 214 is positioned to open the grippers on the conveyor D and to then permit the grippers to close just before a cam shown at 215 opens the grippers carried by the transfer conveyor C.

Blanks held on the Conveyor D are treated successively in the tanks 15 and 20 and are then moved up to the transfer station indicated at 38 in Figure 4^b where they are transferred to grippers carried by the conveyor E. The grippers on the conveyor E also may conform to the construction shown in Figures 5 and 6. A cam positioned as indicated at 216 is adapted to enter relatively between the gripper operating rollers 166 and 168 for conditioning the grippers to receive blanks when the grippers arrive at the transfer station 38. A cam positioned as indicated at 217 is adapted to engage the rollers 166 and 168 of a gripper assembly carried by the conveyor D for opening the grippers on the conveyor D after the grippers on the conveyor E have been closed, thus effectively completing the transfer of blanks from the conveyor D to the conveyor E. The transfer is accompanied by a reversal or inversion of the blanks so that the edge portions thereof which were treated in the tanks 15 and 20 will be the portions which are held on the conveyor E, and the untreated edge portions will be extended downwardly for treatment in the tanks 26 and 30.

When blanks carried by the conveyor E have been treated and moved beyond the tank 30, the associated gripper operating rollers 166 and 168 will move into engagement with a cam positioned as at 218 in Figure 4^a so that the grippers will be opened and the blanks released at the discharge station 41.

Returning now to the treatment of blanks carried on the conveyor D, a bus bar 18 mounted above the cleaning tank 15 is adapted to engage the gripper frame 153 as a group of blanks is passing along the tank 15, so as to establish a circuit including the bus bar 18, gripper frame 153, the blanks 14 and the anodes 17. Preferably, insulated wires 219 extending in the direction of blank travel through the tank are provided for guiding the blanks and maintaining them against lateral sway. When a group of blanks has been withdrawn from the fluid in the tank 15, the treated lower edge portions of the blanks pass between pairs of squeegee rollers 220 for removing adhering cleaning fluid.

The blanks then pass on for having their lower edge portions plated in the tank 20. Associated with this tank is the bus bar 23, anodes 22, insulated guide wires 221 and squeegee rollers 222 for removing adhering electrolyte.

While the blanks are traveling along the lower stretch of the top conveyor E, their lower edge portions are treated successively in the tanks 26 and 30. Associated with the tank 26 is the bus bar 28, anodes 27, a set of insulated guide wires 223 and squeegee rollers 224. Similarly associated with the tank 30 is the bus bar 33, anodes 32, a set of insulated guide wires 225 and squeegee rollers 226.

It will be apparent that the bus bars, anodes, guide wires and squeegee rollers associated respectively with each of the tanks 20, 26 and 30, perform functions the same as the corresponding parts associated with the tank 15 as more fully explained above.

Mechanism is provided for varying the spac-

ing between the carriers C and D so as to adapt the apparatus for handling and treating can body blanks of different lengths. In the form shown, the sprockets 188 engaged by the conveyor D are carried respectively by spaced sliders 227 and 228 mounted in guides 229 and 230 on the frame 194. The sliders 227 and 228 are adjustable towards and away from the conveyor C by screws, one of which is indicated at 231 in Figure 4^a. The screw may be operated by a bevel gear couple 232 and an actuating shaft 233.

The right hand end of the bottom conveyor D also is mounted for movement toward and away from the conveyor E at the transfer station indicated at 38. The sprockets 187 are mounted respectively on sliders 234 and 235 adapted to move vertically in frame guides 236 and 237. Adjusting screws, one of which is shown at 238, may be provided for raising and lowering the sliders 234 and 235. The screw 238 may be rotated for adjustment by a bevel gear couple 239 and an actuating shaft 240.

The tension of the bottom treating conveyor D may be adjusted by shifting the sprocket 188 horizontally. The sprocket 188 may be mounted on a slider 241 adapted to be shifted horizontally by a screw 242 rotatable by a bevel gear couple 243 and an actuating shaft 244.

The tension of the top treating conveyor E may be adjusted by shifting the sprocket 200 horizontally. As indicated in Figure 4^b the sprocket 200 may be journaled on a slider 245 shiftable horizontally by a screw 246 adapted to be rotated by a bevel gear couple 247 and an actuating shaft 248.

Each of the tanks 15, 20, 26 and 30 is mounted for vertical adjustment to adapt the apparatus for the treatment of blanks of different lengths. The mechanism for adjusting the tank 30 includes a plurality of adjusting screws 249 journaled in brackets 250 carried by the frame 185. The screws 249 have threaded engagement with interiorly threaded sleeves 251 fast with the tank 30. Bevel gears 252 are rotatable by adjusting shafts 253 for rotating the screws 249 and thus raising and lowering the tank 30.

The tanks 15, 20 and 26 are adapted to be adjusted vertically by mechanism the same as that shown for adjusting the tank 30.

Figures 7 to 13 inclusive show a modified blank gripping and holding unit which may be used in place of the unit 131 described with reference to Figures 5 and 6. The modified construction comprises a cross frame or bar 255 fitted at its opposite ends with blocks 256 connected respectively to the conveyor chain 130 by angle brackets 257. The gripper assembly 254 is indicated as being connected to the chain 130 of the transfer conveyor C, but it will be understood that the gripper assembly also may be mounted on the treating conveyors D and E. When used in connection with the conveyor C it is not necessary to insulate the cross frame member 255 but when used on the conveyors D and E, the cross frame member should be insulated from the conveyor chains and for this purpose the end blocks 256 may be constructed of insulating material.

L-shaped gripper parts 258 are secured to the frame 255 by screws 259 and are spaced correspondingly to the spacing of the blanks of a group of blanks to be treated. Each L-shaped part 258 includes a clamping face 260, and a guide portion 261 adapted to direct a blank into face to face relationship with the clamping portion 261 of an

adjacent part 258. Rounded edge portions 260 and 261 on the clamping faces 260 and the guide portions 261 further assist in guiding the blanks between adjacent parts 258.

An actuating rod 262 is mounted to slide through the L-shaped parts 258 and is fitted with angle pieces 263 each having secured to it a pair of rubber blocks 264 held in place by screws 265 and plates 265a. Movement of the rod 262 toward the left as viewed in Figures 7 and 8 shifts each pair of blocks 264 away from the associated clamping face 260 on the adjacent part 258 so as to condition the grippers to receive the blanks. In order to hold the blanks on the gripping assembly 254, the rod 262 is shifted toward the right whereby the blocks 264 will press the blanks against the respectively associated faces 260.

The rod 262 is urged toward the right by a spring 266 interposed between a collar 267 fast with the rod 262 and a socket 268 which is exteriorly threaded and mounted in an interiorly threaded lug 269. The tension of the spring 266 may be adjusted by rotating the socket 268 in the lug 269 and the tension adjustment may be maintained by turning a locking screw 70 to effect binding of the lug 269 on the socket 268.

The movable gripping devices 264 may be shifted away from the fixed gripping devices by cam mechanism similar to that previously described with reference to the gripping mechanism 131. A fixed roller 271 is journaled as at 272 on the gripper frame 255 and a roller 273 is journaled as at 274 on the shiftable rod 262. The roller 273 and the rod 262 are adapted to be shifted by a wedge cam similar to the cam 170 which operates the rollers 166 and 168 in the embodied shown in Figures 5 and 6.

The gripper mechanism 254 is equipped with means for pushing against the trailing edges of blanks held by the grippers 258-264. A pusher bar 275 is suspended from the frame 255 by hanger arms 276. Guide clips 277 secured to the pusher bar 275 are spaced correspondingly to the grippers so as to receive the trailing edges of blanks held by the grippers, thereby maintaining the blanks parallel to each other and holding them against shifting in the grippers. Preferably the arms 276 are adjustable on the frame 255. For this purpose the arms 276 are secured respectively to angle brackets 278 by screws 280, and the angle brackets 278 are formed with slots 281 for accommodating clamping screws 282 engaging the frame 255. By loosening the screws 282, the angle brackets 278 and consequently the hanger arms 276 and pusher bar 275 may be adjusted with respect to the frame 255, thus adapting the gripper assembly for holding blanks of different widths.

Another modified gripper assembly generally designated 283 and shown in Figures 14, 15 and 16 may be used in place of the assemblies 131 previously described. The gripper assembly 283 includes a cross frame member 284 provided at its opposite ends with blocks 285 connected by angle brackets 286 to the conveyor chains indicated at 130. When applied to the transfer conveyor C it is not necessary for the assembly 283 to be insulated from the chains 130. However, when applied to the conveyors D and E the gripper assembly should be insulated from the conveyor chains and for this purpose the blocks 285 may be formed of insulating material.

A plurality of fixed gripper elements 287 is secured to the cross frame member 284 by screws 287a. Each gripper element 287 is formed with a clamping face 288 and a guide face 289. Prefer-

ably, the faces 288 and 289 have curved blank entrance guiding portions 288a and 289a respectively.

Movable gripper elements 280 are mounted respectively on levers 291 pivoted on the frame 284 as at 292. Each gripper element 290 comprises an angle piece 293 and a pair of rubber blocks 294 secured to the angle piece by screws 295 and plates 296. The levers are arranged to be operated in unison by a link 297 pivoted to the levers as at 298. The levers 291 are shown as being U-shaped; and, for centering the link 297 with respect to the legs of the lever, spacers 299 may be interposed between the sides of the link 297 and the legs of the lever. Springs 300 connected between the pivots 292 and 298 associated with each lever urge the levers to rock in a direction to move the associated clamping blocks 294 toward the clamping faces 288 of the respectively adjacent fixed clamping members 283. Thus the springs 300 tend to move the gripper devices 290 into gripping position.

Mechanism for moving the grippers to open position includes a roller 301 journaled as at 302 on the frame 284 and a roller 303 carried by a lever 304 pivoted on the frame as at 305. Fast with the lever 304 is an arm 306 engageable with the adjacent end of the link 297. When a cam similar to the cam 170 disclosed in Figures 5 and 6 is moved between the rollers 301 and 303, the lever 304 and arm 306 are rocked so as to cause the arm 306 to push the link 297, thereby rocking the levers 291 and moving the blocks 294 away from their associated fixed gripper elements 283.

The embodiment shown in Figures 14, 15 and 16 may include a pusher bar similar to that incorporated in the construction shown in Figures 7 to 13 inclusive. A pusher bar 308 is connected to the frame 284 by hanger arms 309 secured by screws 310 to angle brackets 311, in turn secured to the frame 284 by screws 312. The bar 308 is provided with spaced slots 313 for receiving the trailing edges of the blanks of a group carried by the gripping assembly 283.

Gripping assemblies as shown in Figures 14, 15 and 16 may be equipped with brushes 314 for connecting all of the blanks of a group with a single bus bar when the blanks are being subjected to the cathodic cleaning or the electrolytic plating treatment.

The manner of performing the operations and the apparatus disclosed herein are representative of the preferred apparatus for practicing the invention, but it will be understood that changes may be made without departing from the invention as defined in the claims.

We claim:

1. In apparatus for preparing a plate blank for forming a can body, treating bath means; conveyor means; means carried on said conveyor means for gripping an upper portion of a blank and holding the blank suspended from said gripping means with a first edge portion of said blank spaced below and completely exposed and unencumbered by said gripping means; means for reversing the gripping of said blank on the conveyor means whereby when reversed the blank will be held by said gripping means and suspended therefrom with a second edge portion of said blank spaced below and being completely exposed and unencumbered by said gripping means; means for driving said conveyor means; and means mounting the conveyor means to move a blank being conveyed in a path such that said first edge portion of the blank while completely exposed will be

projected into said treating bath means and removed therefrom prior to reversal of said blank, and said second edge portion while completely exposed will be projected into said treating bath means and removed therefrom after said reversal.

2. In apparatus for preparing a plate blank for forming a can body; two adjacent conveyors; first means on one of said conveyors for releasably holding a blank with a first edge portion thereof extended from said one of said conveyors and completely exposed and unencumbered by said first holding means; second means on the other of said conveyors for releasably holding said blank with a second edge portion thereof extended from said other of said conveyors and completely exposed and unencumbered by said second holding means; means for driving said conveyors in time with each other so that the extended exposed edge of a blank held by said first releasable holding means is presented for engagement by said second releasable holding means; means operable upon said first and second releasable holding means when said blank is so presented for effecting releasing of the blank by said first holding means and engaging of the blank by said second holding means to transfer said blank from said first conveyor to said second conveyor; and treating bath means so positioned with respect to said conveyors that said first and second edge portions of the blank are projected while completely exposed into said treating bath means respectively before and after transfer of said blank from said first conveyor to said second conveyor.

3. In apparatus for preparing a plate blank for forming a can body, two adjacent conveyors; first gripper means on one of said conveyors for releasably holding a blank with a first edge portion thereof extended from said one of said conveyors and completely exposed and unencumbered by said first gripper means; second gripper means on the other of said conveyors for releasably holding said blank with a second edge portion thereof extended from said other of said conveyors and completely exposed and unencumbered by said second gripper means; means for driving said conveyors in time with each other so that a blank held by said first gripper means is presented for engagement by said second gripper means; treating bath means containing treating fluid so positioned with respect to said conveyors that during travel of a blank first on one conveyor and then on the other conveyor said edge portions will be projected successively and while completely exposed into said fluid; means for operating said first gripper means to grip said blank while said first edge portion thereof is projected while completely exposed into said fluid and to release said blank when it is presented for engagement by said second gripper means; and means for operating said second gripper means to maintain it in non-gripping condition just prior to presentation of the blank and for actuating it to grip the presented blank and hold it gripped while said second edge portion is projected while completely exposed into said fluid.

4. In apparatus for preparing a plate blank for forming a can body, two adjacent conveyors; first gripper means on one of said conveyors for releasably holding a blank with a first edge portion thereof extended from said one of said conveyors and completely exposed and unencumbered by said first gripper means; second gripper means on the other of said conveyors for releasably holding said blank with a second edge portion thereof extended from said other of said conveyors and completely exposed and unencumbered by said second gripper means;

per means; means for driving said conveyors in time with each other so that a blank held by said first gripper means is presented for engagement by said second gripper means; treating bath means containing treating fluid so positioned with respect to said conveyors that during travel of a blank first on one conveyor and then on the other conveyor said edge portions will be projected successively and while completely exposed into said fluid; spring means for operating said first gripper means to grip said blank while said first edge portion is approaching said treating bath means, while said first edge portion is projected while completely exposed into said fluid; and while said blank is being moved on for presentation to said second gripper means; cam means for operating said first gripper means to release said blank when it is so presented; spring means for operating said second gripper means to grip a presented blank and hold it while said second edge portion is being moved to and projected while completely exposed into said fluid; and cam means for operating said second gripper means to non-gripping position to receive a presented blank.

5. In apparatus for preparing a plate blank for forming a can body, an upper endless conveyor having top and bottom stretches; a lower endless conveyor having top and bottom stretches, the bottom stretch of said upper conveyor extending generally parallel to and above the top stretch of said lower conveyor; lower treating bath means under and adjacent the bottom stretch of said lower conveyor; upper treating bath means under and adjacent the bottom stretch of said upper conveyor; lower holding means on said lower conveyor for releasably holding a blank with a first edge portion thereof extended and exposed; upper holding means on said upper conveyor for releasably holding said blank with a second edge portion thereof extended; means mounting said lower conveyor to move a blank held by said lower holding means and to project said blank first edge portion while exposed into said lower treating bath means and then to withdraw said blank and present it for engagement by said upper holding means; means mounting said upper conveyor to move said upper holding means to receive a blank presented by said lower holding means and to move it to and project said second edge portion into said upper treating bath means; means for operating said lower holding means to release a presented blank; and means for operating said upper holding means to engage and hold a presented blank.

6. In apparatus for preparing a plate blank for forming a can body, an upper endless conveyor having top and bottom stretches; a lower endless conveyor having top and bottom stretches, the bottom stretch of said upper conveyor extending generally parallel to and above the top stretch of said lower conveyor; lower treating bath means under and adjacent the bottom stretch of said lower conveyor; upper treating bath means under and adjacent the bottom stretch of said upper conveyor; lower holding means on said lower conveyor for releasably holding a blank with a first edge portion thereof extended; upper holding means on said upper conveyor for releasably holding said blank with a second edge portion thereof extended and exposed; means mounting said lower conveyor to move a blank held by said lower holding means and to project said blank first edge portion into said lower treating bath means and then to withdraw said blank and present it for engagement by said upper holding means; means mounting said upper conveyor to move said upper holding means to receive a blank presented by said lower holding means and to move it to and project said second edge portion into said upper treating bath means; means for operating said lower holding means to release a presented blank; and means for operating said upper holding means to engage and hold a presented blank.

75

ing said upper conveyor to move said upper holding means to receive a blank presented by said lower holding means and to move it to and project said second edge portion while exposed into said upper treating bath means; means for operating said lower holding means to release a presented blank; means for operating said upper holding means to engage and hold a presented blank; and adjustable means for effecting variation of the vertical spacing between one of said conveyor 10 lower stretches and the associated treating bath means to thereby vary the depth to which the blank is projected into the treating fluid.

7. In apparatus for preparing individual plate blanks for forming can bodies, treating means; a treating conveyor; releasable holding means on said conveyor for holding a plate blank on said conveyor for travel therewith to the treating means; another conveyor; other releasable holding means on said other conveyor for holding a 20 plate blank on said other conveyor; means mounting said conveyors to operate with respective stretches thereof adjacent each other; means for driving said conveyors for said stretches to travel in the same general direction and at the same speed and for timing the conveyor drives so that a blank held by said other holding means is presented to the holding means on said treating conveyor; means for conditioning said other holding means to hold a blank until it is presented to the holding means on said treating conveyor and then to release said blank; and means for conditioning the holding means on said treating conveyor to

receive the presented blank and to then hold the blank when it is released by said other holding means.
